MODULAR DESK UNIT

John Nance, Quakertown, Pa., assignor to JG
Furniture Co. Inc., New York, N.Y.

Original design application Dec. 29, 1970, Ser. No. 26,689.
Divided and this application Apr. 14, 1972, Ser. No.
244,330

Term of patent 14 years

Int. Cl. D6—04
U.S. Cl. D6—162

FIG. 1.

FIG. 2.

FIG. 3.

FIG. 4.

FIG. 1 is a perspective view of a modular desk configuration embodying my new design;

FIG. 2 is a top plan view of the modular desk configuration of FIG. 1;

FIG. 3 is a side view of the modular desk configuration of FIG. 1; and

FIG. 4 is an end view of the modular desk configuration of FIG. 1.

This application is a division of my copending U.S. patent application, Serial No. D. 26,689, filed Dec. 29, 1970.

I claim:

The ornamental design for a modular desk unit, as shown.
